UNITED STATES PATENT OFFICE

116,037

DESIGN FOR A FOLDING BENCH OR SIMILAR ARTICLE OF FURNITURE

Ada H. Leissing, Franklin, Mass.

Application March 29, 1939, Serial No. 83,910

Term of patent 7 years

To all whom it may concern:

Be it known that I, Ada H. Leissing, a citizen of the United States, residing at Franklin, in the county of Norfolk and State of Massachusetts, have invented a new, original, and ornamental Design for a Folding Bench or Similar Article of Furniture, of which the following is a specification, reference being had to the accompanying drawing, forming part thereof,

Fig. 1 is a perspective view of a folding bench or similar article of furniture showing my new design;

Fig. 2 is an end view thereof; and

Fig. 3 is a fragmentary front view thereof.

I claim:

The ornamental design for a folding bench or similar article of furniture, as shown.

ADA H. LEISSING.
